(57) **CLAIM**

The ornamental design for a storage case, as shown and described.

DESCRIPTION

FIG. 1 is a perspective view of portions of the front, top, and left side of a storage case showing my new design;

FIG. 2 is a perspective view of portions of the rear, top, and right side of the storage case showing my new design;

FIG. 3 is a front view thereof;

FIG. 4 is a rear view thereof;

FIG. 5 is a top view thereof;

FIG. 6 is a right view thereof;

FIG. 7 is a left view thereof;

FIG. 8 is a perspective view thereof showing a lid portion in an opened position; and,

FIG. 9 is a perspective view thereof showing the storage case partially disassembled and with the lid portion in an opened position.

The broken lines shown are included for the purpose of illustrating portions of the article which form no part of the claimed design.
